CLAIM

The ornamental design for a display fixture, as shown and described.

DESCRIPTION

FIG. 1 is a perspective view of a display fixture;
 FIG. 2 is a front view thereof, the rear being unornamented;
 FIG. 3 is a right side view thereof;
 FIG. 4 is a left side view thereof; and,
 FIG. 5 is a top view thereof, the bottom being unornamented. The broken lines shown in the drawings are included for purposes of illustrating portions of the display fixture or for purposes of illustrating environment and form no part of the claimed design.
